LOESER KALINA, OF NEW YORK, N. Y.

FOLDABLE GARMENT-HANGER.

1,162,613.

Specification of Letters Patent. Patented Nov. 30, 1915.

Application filed December 24, 1914. Serial No. 878,971.

To all whom it may concern:

Be it known that I, LOESER KALINA, a citizen of the United States, and a resident of the city of New York, borough of Brooklyn, in the county of Kings and State of New York, have invented a new and Improved Foldable Garment-Hanger, of which the following is a full, clear, and exact description.

10 The object of the invention is to provide a new and improved foldable garment hanger, more especially designed for supporting trousers and like garments, and arranged to fold into a comparatively small package for conveniently carrying it along in a pocket, valise, trunk or the like, and adapted to be readily extended and hung up for use on a hook or other suitable support.

In order to accomplish the desired result, 20 use is made of a casing, arms pivoted on the casing to fold therein or to extend in opposite directions and at angles to the said casing, and fastening devices pivoted on the free ends of the said arms to fold thereon or 25 depend from the same at the time the arms are in extended position.

A practical embodiment of the invention is represented in the accompanying drawings forming a part of this specification, in 30 which similar characters of reference indicate corresponding parts in all the views.

Figure 1 is a perspective view of the garment hanger with the parts in folded position; Fig. 2 is a similar view of the same 35 with the parts in extended position; Fig. 3 is a sectional side elevation of a portion of the same on the line 3—3 of Fig. 2; Fig. 4 is an end view of one of the clamping devices; Fig. 5 is an enlarged cross section 40 of the garment hanger with the parts in folded position; Fig. 6 is an enlarged cross section of the garment hanger on the line 6—6 of Fig. 3; and Fig. 7 is a sectional side elevation of the garment hanger with the 45 parts in folded position, the section being on the line 7—7 of Fig. 1.

The casing A of the garment hanger is approximately U-shaped, that is, is open at the sides and the bottom, and the lower end 50 of the casing A is provided with two trans-

versely extending spaced pivots B, B', on which are mounted to swing arms C, C' adapted to be folded through the open sides of the casing into the casing (see Figs. 1, 5 and 7), or to be extended therefrom in opposite directions in an approximately horizontal position, as plainly indicated in Figs. 2 and 3. The arms C and C' are made hollow and preferably of inverted U shape in cross section, and on the free ends of the 60 said arms C and C' are held transversely extending pivots E, E' on which are mounted to swing fastening devices D and D' adapted to depend from the free ends of the said arms C and C' at the time the said 65 arms are in extended position, as shown in Figs. 2 and 3, and the said fastening devices D and D' are adapted to fold into the hollow arms C, C' at the time the latter 70 are swung into folded position within the casing A. Each of the fastening devices 75 D, D' is preferably in the form of a clamp having two jaws D² pressed on by a spring F to normally hold the jaws in closed position with a portion of the garment clamped 80 between the jaws so as to support the said garment. The jaws D² of each fastening device D are provided with fingerpieces D³ extending beyond the free ends of the arms C and C' so as to permit the user to conveniently take hold of the said fingerpieces 85 and press the same toward each other with a view to open the jaws D² when it is desired to pass a portion of the garment between the clamping jaws D² or to remove the 90 said garment portion from the jaws D². As shown in the drawings, the spring F is preferably a U-shaped spring attached at its free ends to the fingerpieces D³ and extending between the said fingerpieces, as 95 will be readily understood by reference to Figs. 2, 5 and 6. A ring G surrounds the reduced portions D⁴ of the jaws D² of each fastening device D and this ring is slidable up and down on the said reduced portions 95 so as to allow of conveniently opening the jaws D² when the ring is in uppermost position and to securely lock the jaws D² against opening at the time said jaws are in closed position. Each of the pivots E, E' passes 100

through elongated apertures D^e formed in the fingerpieces D^a above the pivot D^e of the clamping jaws D^2 to allow the fastening devices to freely swing on the pivots E , E' to allow the fastening devices to easily swing into or out of position in the hollow arms C , C' . The bottoms of the jaws D^2 are preferably provided with registering tongues and grooves D^f , D^g to insure a secure clamping and holding of the garment material when placed between the jaws D^2 (see Fig. 4).

In order to impart an initial opening movement to the arms C and C' when folded in the casing A , use is made of a doubled-up flat spring H held on a transverse pin I attached to the casing A intermediate the pivots B and B' . The free ends of the spring H are curved outwardly in opposite directions so that when the arms C , C' are swung upward into folding position then the backs of the arms engage the free ends of the spring H to compress the same. The spring H is held in an approximately horizontal upright position by indentations or lugs J struck up on the casing A in an inward direction so as to engage the outer faces of the side arms of the spring H at a point a short distance above the pin I .

In order to close the open sides of the casing A with a view to hold the side arms C and C' in folded position, use is made of a cover K , preferably in the form of an inverted U-shaped frame having its free ends mounted to swing on a pin K' held in a bearing K^2 connected by a swivel K^3 with the top of the casing A . The cover K is adapted to be swung downward on its pin K' so that the side arms of the cover K fit over the side openings of the casing A to close the said casing at the sides and thus hold the arms C , C' in folded position within the casing A , as plainly indicated in Figs. 1, 5 and 7. The casing A and the cover K are approximately the same as the parts shown and described in the Letters Patent of the United States, No. 1,049,867, granted to me on January 7, 1913, so that further detail description of the same is not deemed necessary. It is understood that the cover K when swung into open vertical position can be readily turned by the swivel K^3 on the top of the casing A to permit of conveniently hooking the cover K onto a hook, nail or other suitable support and to suspend the garment hanger in a closet or other structure. It will also be noticed that by the arrangement described the casing A with the arms C , C' and the fastening devices D , D' in open position can be readily turned around to move the fastening devices into the desired position for convenient manipulation by the user when placing a garment in position on the said fastening devices or

removing it therefrom, as previously explained.

In practice, the garment will be engaged with both fastening devices D and D' so as to properly support the garment to prevent the same from undesirable creases.

The garment hanger shown and described is very simple and durable in construction and can be cheaply manufactured, and when not in use the arms C , C' can be readily swung upward into folded position within the casing A and in doing so the fastening devices D , D' swing into folded position within the arms C , C' . When the side arms and the fastening devices are in folded position the casing A can be readily closed by swinging the cover K downward to close the sides of the casing and to hold the arms C , C' against outward movement. When it is desired to use the garment hanger, the user simply swings the cover K upward into open position to allow the free ends of the spring H to start the arms C and C' on their outward and downward swinging movement, it being understood that after the arms C and C' have been started they readily swing into final horizontal open position by their own weight and that of the fastening devices D , D' which latter during the downward swinging movement of the arms C , C' swing into open position by their own weight. The downward swinging movement of the arms C , C' is limited by providing the said arms with straight heels C^2 adapted to abut against the sides of the spring H at the pin I , as will be readily understood by reference to Fig. 3. Other suitable means, however, may be provided for limiting the opening movement of the said side arms C and C' .

Having thus described my invention, I claim as new and desire to secure by Letters Patent:

1. A garment hanger, comprising a casing open at the sides, hollow arms open at the bottom and mounted to swing on the said casing, the arms in one position being folded in the casing and in another position extending approximately in a horizontal plane and in opposite directions from the open sides of the casing, and clamping devices each having a pair of spring-pressed pivoted jaws having handles and fulcrumed on the free ends of the said arms, the said jaws being adapted to fold within the said hollow arms, the said handles projecting above the arms at the time the latter are in extended position.

2. A garment hanger, comprising a casing open at the sides, arms pivoted independently one of the other in the lower end of the casing to fold therein or to extend in opposite directions and at angles from the casing, the pivoted ends of the said arms

having straight heels, and a flat spring in the lower end of the casing and adapted to bear against the said arms at the time the latter are in folded position within the casing, the said spring forming a stop for the said heels to limit the downward swinging movement of the arms.

In testimony whereof I have signed my name to this specification in the presence of two subscribing witnesses.

LOESER KALINA.
